a corporation of New York

Original application Apr. 23, 1953, Ser. No. 350,722, now
Patent No. 2,937,352, dated May 17, 1960. Divided
and this application Feb. 27, 1958, Ser. No. 718,080
1 Claim. (Cl. 29—155.57)

This invention relates to magnetic cores, and more particularly, to an improved method of making magnetic cores and linking the same with electrical coils.

This application is a division of our patent application Serial No. 350,722, filed April 23, 1953, and now Patent No. 2,937,352.

A known form of butt joint laminated magnetic core structure comprises a continuous and relatively narrow strip of flat thin metallic magnetic material wound continuously into a rectangular or annular core section with a window opening therein. Each of the layers or turns of the magnetic strip material is superimposed and concentric with respect to each other.

When used in a transformer apparatus, electrical winding coils are linked with said strip wound laminated core section. To do this, a butt joint is formed in the closed core section by cutting through all the laminations. Then the core section can be pried or hinged open and a pre-wound electrical winding coil assembly can be linked therewith.

Prior to formation of the butt joint by cutting, some form of holding means has to be employed to hold the various laminations together so they will not become disassembled when the core is hinged open. Also, the various laminations must be held together so they won't become misaligned from their original uncut positions so that the butt joint can be accurately closed.

In the known prior art the holding means employed are rigid means like welding, mechanical clamps, or hardsetting enamels, varnishes, or cements. For instance, prior to cutting, the laminated core section may be impregnated with a hard setting varnish. After the varnish sets it rigidly bonds adjacent laminations of the core section together.

A disadvantage of hard setting or rigid holding means is that relatively little play or freedom of movement is permitted between adjacent laminations when the core section is hinged or pried open. As a consequence, when the core section is hinged open mechanical stresses are formed in the various laminations which cause electrical losses in the magnetic core.

Another problem encountered in the prior art is that during the cutting operation the cut laminations have burrs formed thereon. The burrs of each cut lamination make electrical contact with adjacent laminations. That is, a short circuit is formed in the core at the cut portions. This short circuit condition also causes electrical losses in the magnetic core.

It is an object of this invention to provide a method of constructing a butt joint strip wound laminated core section wherein adjacent laminations are elastically bonded together and a short circuit at the faces of the butt joint is prevented.

In the method of linking a curved core with electrical coils by forming a single butt joint in the core and then hinging it open, our invention comprises the improvement of bonding the turns together with an elastic and dielectric material so as to retain them together while still affording them a limited amount of movement to facilitate opening and closing of the core.

Our invention also comprises a method of making a butt joint strip wound laminated magnetic core section

2

comprising impregnating a strip wound laminated core section with an elastic electrical insulating bonding material, applying compressive forces to a portion of said core section, cutting said compressed portion to form a butt joint, and then removing said compressive forces.

The invention will be better understood from the following description taken in connection with the accompanying drawing and its scope will be pointed out in the appended claim.

10 In the drawing, FIGURE 1 is a perspective view of a butt joint hinged rectangular like laminated core section formed by winding a relatively narrow flat thin strip of metallic magnetic material into a plurality of superimposed and concentric laminations. FIGURE 2 is an illustration of how a butt joint strip wound laminated core section is pried or hinged open to receive a prewound electrical winding coil assembly to be linked therewith. FIGURE 3 is an enlarged view of a butt joint portion of a laminated core section with clamps applied to said portion. FIGURE 4 is an enlarged view of the ends of the cut laminations of an elastic binder impregnated core section portion while compressive forces are applied to said portion. FIGURE 5 is an enlarged view of the ends of the cut laminations after the compressive forces have been removed.

Referring now to FIGURE 1 of the drawing, there is shown therein a rectangular like strip wound laminated core section 1 having a cut or butt joint 2 so that the core section 1 can be hinged or pried open about a hinge portion 3, as illustrated in FIGURE 2, so that a pre-wound electrical winding coil assembly, not shown, can be linked with the core section 1. A strap or clamping means 4 aids in holding the core section 1 closed after the winding coil assembly, not shown, is linked with core section 1.

The rectangular-like core section 1 is formed by spirally winding a relatively narrow flat thin strip of metallic magnetic material into a plurality of superimposed and concentric laminations. Adjacent laminations are spaced a sufficient distance from each other to permit impregnation and closing of the core joint with a minimum of strain. As seen in FIGURE 1, the core section 1 has two vertical laminated leg portions joined by two horizontal laminated yoke portions. The cut 2 is preferably made in the upper left-hand corner of core section 1 so that the core section 1 can be hinged open about a diagonally opposite corner 3. After the core section is wound it is annealed before impregnation and cutting to remove stresses set up in the laminations during the winding operation.

Prior to formation of the butt joint or cut 2 the core section 1 is impregnated with an elastic dielectric bonding material. The elastic bonding material holds adjacent laminations of core section 1 together so that they won't become disassembled during the opening or hinging operation.

By viewing FIGURES 1 and 2 it will be seen that the outer laminations of the cut core section 1 are longer than the inner laminations. During the hinging or opening operation the outer and longer laminations require a greater degree of movement or play than the shorter inner laminations. If rigid means are used to hold the various cut laminations together during the opening operation comparative free and unstressed movement of the longer laminations with respect to the shorter laminations is not permitted. That is, with rigid holding means the various laminations are buckled and distorted and have mechanical stresses formed therein. These mechanical stresses cause electrical losses in the magnetic core section.

70 However, with elastic holding means, limited free and easy movement of the various laminations with respect to each other is permitted during the hinging operation

causing a minimum of mechanical stresses. Further, when the core section 1 is closed the elastic bonding material permits and aids the various laminations to assume their original uncut positions relative to each other so that the butt joint 2 can be accurately closed.

The faces of the butt joint can be painted with the elastic bonding material to aid in keeping the core section closed. A further advantage of having an elastic adhesive impregnant as the holding means is that audible noise is decreased. When a transformer is operating vibrations are set up in the magnetic core. Elastic substances are good sound dampers. Consequently, by impregnating the core and painting the faces of the butt joint with an elastic binder the amount of audible noise is decreased.

Most impregnating materials set up a strain in the surface of the core laminations due to shrinkage. An elastic adhesive minimizes this effect. Also, these strains can be further held to a minimum by impregnating only a part of the core, or by a purposely incomplete impregnation so that the adhesive between a pair of adjacent laminations is present only in streaks.

After impregnation of the core with an elastic adhesive and setting of the same and prior to cutting of the core to form a butt joint the portion of the core to be cut is subjected to compressive forces. Thus, as seen in FIGURE 3, the corner or portion to be cut is compressed, as by a pair of clamps comprising horizontal bars 5 joined at opposite ends by threaded bolts 6. Nuts 7 when threaded down on bolts 6 place the portion to be cut in compression. It should be noted that the compressive forces are applied substantially perpendicular or against the flat surfaces or planes of the laminations to be cut. These compressive forces compress the layers of elastic bonding material located between the various laminations of the core portion to be cut.

The purpose of compressing the elastic bonding material in the area to be cut is illustrated in FIGURES 4 and 5. As seen in FIGURE 4, when the cut 2 is made burrs 8 are formed at the ends of the cut laminations 9 which have compressed elastic bonding material 10 therebetween. The burrs 8 make electrical contact with adjacent laminations. Since all the laminations are then electrically interconnected a short circuit is formed in the laminated butt joint core at the faces of the butt joint. This short circuit condition results in electrical losses in the magnetic core.

However, by using an elastic dielectric bonding material and compressing the bonding material prior to cutting this short circuit condition is uniquely relieved. In FIGURE 5 is shown what occurs after the clamps of FIGURE 3 are removed after the cutting operation. The compressed elastic bonding material 10 expands to its substantially original non-compressed state. Expansion of the material 10 causes the cut core laminations 9 to be separated a sufficient distance to take the burrs 8 out of electrical contact with adjacent laminations 9. Thus, the short circuit condition of FIGURE 4 is removed.

It is to be noted that the whole core structure need not necessarily be impregnated with the elastic binder. For instance, only a portion of the core at the area to be cut need be impregnated if this partial impregnation of

the core will be sufficient to hold the core laminations together when the core is hinged open. Such partial impregnation will still yield the benefits of the disclosed method of cutting and relieving short circuit conditions at the faces of the butt joint.

Further, while the invention is disclosed as applied to a rectangular-like core section it will be obvious that the invention can be applied to circular wound core sections and also core sections cut into a plurality of core sub-sections which are to be butt jointed together. Accordingly, by the term annular core section we do not intend to restrict ourselves to a circular wound core section having a window opening therein, but intend that the term comprise any closed core section having a window opening therein.

The elastic impregnant used does not constitute part of this invention but is a substance that can be readily purchased on the market. It should not be hard setting, but should be elastic to permit limited freedom of movement between the various laminations during the hinged opening operation, and should be adhesive enough to hold the various laminations from becoming disassembled. An elastic adhesive that has given good results is a synthetic thermo-setting rubber-base adhesive of the butadieneacrylonitrile type. The elastic adhesive selected must not be corroded by transformer insulating oils.

While there has been shown and described a particular embodiment of the invention, it will be obvious to those skilled in the art that changes and modifications may be made without departing from the invention, and that it is intended by the appended claim to cover all such changes and modifications as fall within the true spirit and scope of the invention.

What we claim as new and desire to secure by Letters 35 Patent of the United States is:

A method of making a magnetic core and linking the same with a preformed electrical coil, said method comprising winding and forming a continuous strip of magnetic material into a curved core having radially nested 40 and spaced spiral turn laminations, annealing said curved core, bonding said laminations with respect to each other by impregnating said laminations with an elastic and dielectric bonding material, placing a part of said core under compression to compress its bonding material, 45 cutting through said compressed part to form a core having a single butt joint and single turn cut laminations relieving said compression to expand said compressed bonding material to separate edge burrs on said single turn cut laminations, hinging said curved core open by hinged movement of said bonded and cut laminations in a direction away from said joint about a part of said core which is opposite to the part of said core having said joint therein, linking said hinged open core with a preformed electrical coil, and then closing said electrical 50 coil linked core by hinged movement of said bonded laminations in an opposite direction to close said joint.
